QUENCHING CHAMBER FOR ELECTRIC GAS SWITCHES

Hubert Korndörfer, Berlin, Germany, assignor to
General Electric Company, a corporation of
New YorkApplication January 31, 1938, Serial No. 188,011
In Germany May 28, 1936

8 Claims. (Cl. 200—149)

This invention relates to quenching chambers for electric gas switches of the type wherein the compressed gas requisite for the quenching of an arc is liberated from gas-producing material forming the walls of the quenching chamber by the switching-off arc itself.

With the known constructional forms of quenching chambers of the above mentioned type the walls of said chambers which give off a gas, as stated, are generally formed by tubes through which the movable contact is drawn after separation from its counter contact. This design has the drawback that the chamber walls are strongly affected not only thermically by the switching-off arc, and mechanically by the rapidly generated high pressure, but are also subjected to additional mechanical strains due to movable switch members. These strains may become very considerable especially if beads of fused metal form at the inner walls of the tubes or, also at the movable switch members, as a consequence of the switching operations.

Furthermore, in the known constructional forms, as long as the tip of the movable contact is located still within the quenching tube, the current of gas under pressure is confined solely at the lower rims of the movable switching member, as the switching gases which are under a high pressure can escape outwardly and in a restricted quantity only at said rims through the narrow annular space necessary for the requisite play between the movable switch pin and the inner walls of the quenching tube. Finally, there exists in the tube, in which the arc is burning between the stationary switch member and the movable one approximately static pressure conditions which are not so serviceable for the quenching of the arc as compared with a gas current.

A principal object of my invention is the provision of an improved quenching chamber of the aforesaid type wherein the arc-extinguishing gas is produced by the action of the arc on a solid gas-producing material so located with respect to the arc chamber that the chamber structure is not subjected to severe mechanical strains. The development of the quenching gas takes place at said place on a large surface and from an easily evaporated material, so that large quantities of a gas having a comparatively low temperature are obtained. Furthermore, provision is made to insure that soon after the commencement of the separation of the contacts a current of quenching gas is produced and so conducted that the arc is drawn into an existing quenching current, where-

by it is quickly and reliably quenched. The conducting members for the current of the gas can be designed in the manner of a Laval-nozzle so that a favorable flow of the quenching gas, as well as complete relief of pressure, and therefore, also a complete cooling of the hot switching gases is obtained and special cooling devices at the quenching chambers can be dispensed with.

The invention is illustrated diagrammatically and by way of example by the accompanying drawing in which Fig. 1 is an axial section through a quenching chamber designed according to this invention, and Fig. 2 is a similar fragmentary view of a slightly modified form of the quenching chamber.

This quenching chamber consists in the present instance of a cylindrical member 1 of an insulating material in which a hollow space 2 having the shape of a Laval-nozzle is provided. The member or insulating body 1 may be reinforced if desired by metallic insertions or by similar members and is closed at one end by a lid 4. In the thus formed space 5 between the narrowest place 6 of the insulating body 1 and the lid 4 is arranged a contact chamber 7 consisting of an insulating material which, if desired, may be reinforced. The chamber 7 contains the stationary contact 8 which co-operates with the movable switching member 9 that is tubular in the example shown. The unoccupied space in the passageway of the contact chamber is closed by an insulating bolt 10 which forms, together with the passagebore of the chamber 7 a restricted annular passage 11 for the movable switching member and which may be, like said chamber, provided with insertions consisting of a material giving off gas in a certain extent under the influence of the heat of the arc.

The lower end of the contact chamber is open and is provided with a structure 12 having a large surface, and consisting of a substance that readily gives off an arc-extinguishing gas under influence of the arc heat. As shown in Fig. 1 the structure 12 comprises broken or granular material having interstices of such size that gas flow is not impeded. In the case of Fig. 2, a grid or honeycomb-like structure is shown. The particular gas-producing material used can be chosen to suit operating requirements. Examples of such materials are fibre, urea, resin and carbonates in general. Between the stationary contact 8 and the structure or grid 12 is an intermediate wall 13 in which a return-valve 14 is inserted.

The manner of operation of a quenching cham-

ber designed according to this invention is as follows:

When the contacts 8 and 9 are separated from one another the volume of air contained in the 5 contact chamber 1 is heated and thereby subjected to pressure which cannot, however, be released along the movable switch member. The pressure increases during the further course of the switching stroke of said switch member. 10 the passage opening of the chamber 1 is also constructed of a material which is evaporated by the heat of the arc, then the formation of a highly compressed hot gas also in this manner is promoted without an essential wear of the 15 inserted members.

These hot switching gases open the non-return valve 14 and stream along the honeycomb or granular structure 12 which consists of a material that readily gives off gas when subjected to 20 the action of heat. While said switching gases are thus streaming along said structure they give rise to a quick development of large amounts of quenching gas escaping from the large surface of the said structure, there also taking place at the 25 same time a reduction of the high temperature. While this takes place, the pressure of the gas contained in the chamber 1 increases quickly and the gas flows with a high velocity around the contact chamber at the outer surface thereof through 30 the passage 5 to the narrowest place 6 of the quenching chamber body 1 beyond which place there is a great drop in pressure by reason of the correspondingly shaped nozzle piece 15 lying above said narrowest section.

35 As soon as the arc is drawn from the contact chamber 1 it is exposed to the action of a powerful gas current which surrounds it in hose-like manner and quenches it. The entrance of the arc in said current of gas is at the zone of the 40 most favorable quenching conditions shortly in front of the narrowest nozzle section. At this point a small amount of the switching gas which has been highly heated directly by the arc is liberated and when it passes along the structure 45 12 such as the honeycomb-insertion which consists of easily gasifiable substances, there takes place, with the present improved quenching chamber, a reliable quenching of the arc with weak currents, as well as strong ones. The gas blast 50 including the arc extinguishing gases produced from the material 12 is therefore initially directed away from the lower portion of the arc by the arc pressure to return to a subsequently formed portion by way of the passages 5 and 2. Thus the 55 gas blast is delivered to the arc by a recurrent path that is in shunt with part of the arc.

The arrangement of the stationary contact, the intermediate partition 13 with its non-return valve, and the honeycomb-insertion relatively to 60 one another as shown by Fig. 1 may, of course, also be designed in another manner than that described above and illustrated by way of example. It may, for instance, be suited to the purpose in view to provide the gas-producing material, 65 such as the honeycomb insertion between the stationary contact and the valve rim or to dispense with it altogether, where cooling means for the hot arc gases is provided and where additional gas is not required.

70 It is also possible to subdivide said insertion (12) and to subject a part of the gas-producing surface at the outset to the action of the hot gas current produced directly by the arc, whereas the other part of the subdivided insertion is en- 75 closed in part by an intermediate wall provided

with a non-return-valve. This second part is utilized for the generation of gas only when the pressure of the gas present in the contact chamber 1 has attained a certain value, as above described, and has opened the valve. Also the 5 reverse valve operation is suited for the purpose in view, in that that part of the honeycomb-shaped insertion which is enclosed by means of the intermediate wall is withdrawn from the hot gases by closing the valve only when the pressure in 10 the contact chamber has attained a certain definite value. In Fig. 1 there is shown by way of example a simple arrangement for replacing the insertion 12 in the manner of a cartridge. A cap 12' to which the insertion is secured is screwed 15 into the end cover 4 so that removal of the cover is unnecessary when the insertion including the gas-producing material is to be replaced. In Fig. 2 the cover 4 is first removed after which the insertion 12 can be removed by suitable means, 20 such as a spanner wrench.

Accordingly, I have provided an improved electric switch of the automatic gas-producing type that is effective to interrupt arcing throughout a wide current range, and that is both simple and 25 rugged in construction with respect to strains to which this type of switch is usually subjected. Also, since the gas-producing material naturally deteriorates with use, depending on the severity of arcing and number of opening operations, the 30 replaceable feature is important from the standpoint of maintenance and continuity of operation.

Another possibility is to make the one part of the honeycomb-like insertion of a material that is gasifiable only with difficulty and the other 35 part of said insertion of an easily gasifiable material. It is then possible to provide, when the honeycomb-like insertion is suitably designed and the valve is appropriately arranged, for the most favorable switching-off conditions at every range 40 of current.

Finally it is preferable that the lid or end cap 4, the inner wall of which is designed to serve as a direction-changing member for the gas stream, be gas-tight, but conveniently detachable with respect to the quenching chamber body 1. This can readily be accomplished by designing the parts for screw-threaded engagement as illustrated. Accordingly the insertion 12, as well as the contact chamber 1, are easily accessible and exchangeable. In Fig. 1 there is shown by way of example a simple arrangement for replacing the insertion 12 in the manner of a cartridge. A cap 12' to which the insertion is secured is screwed 50 into the end cover 4 so that removal of the cover is unnecessary when the insertion including the gas-producing material is to be replaced. In Fig. 2 the cover 4 is first removed after which the insertion 12 can be removed by suitable means, 55 such as a spanner wrench.

Accordingly, I have provided an improved electric switch of the automatic gas-producing type that is effective to interrupt arcing throughout a wide current range, and that is both simple and rugged in construction with respect to strains 65 to which this type of switch is usually subjected. Also, since the gas-producing material naturally deteriorates with use, depending on the severity of arcing and number of opening operations, the replaceable feature is important from 70 the standpoint of maintenance and continuity of operation.

What I claim as new and desire to obtain by Letters Patent of the United States is:

1. An arc-quenching chamber for an electric 75

- switch including relatively movable contacts adapted to form a single arc, comprising a material adapted to yield an arc-extinguishing gas when subjected to the arc heat generated upon separation of said contacts, and casing means for defining a passage leading away from one portion of said arc to said gas-yielding material, and from said material to another portion of said arc.
2. An arc-quenching chamber for an electric switch including relatively movable contacts, comprising a material adapted to yield an arc-extinguishing gas when subjected to the arc heat generated upon separation of said contacts, said material defining a plurality of passages for permitting substantially unobstructed flow of said gas through said material, and casing means for defining a passage leading away from the point of initial arc formation, through said material to return by another path to a subsequently formed portion of said arc.
3. An arc-quenching chamber for an electric circuit interrupter including means for forming a single arc upon opening of the circuit, comprising a material adapted to yield an arc-extinguishing gas when subjected to the arc heat, said material having a comparatively large surface area for contact with the heated arc gases, and casing means for defining a passage leading away from one part of said arc, to said material and returning by a shunt path to another part of said arc.
4. An arc-quenching chamber for an electric circuit interrupter including means for forming an arc upon opening of the circuit, comprising a material adapted to yield an arc-extinguishing gas when subjected to heated arc gases, casing means for defining a passage leading away from one part of said arc to said material and by a recurrent path to another part of said arc, and a non-return valve positioned in said passage between said arc and gas-yielding material so that said passage is opened in response to predetermined arc pressure.
5. An arc-quenching chamber for an electric circuit interrupter including means for forming an arc upon opening of the circuit, comprising a material adapted to yield an arc-extinguishing gas when subjected to heated arc gases, a re-placeable unit including said material, said unit being interposed in and substantially filling a passage interconnecting different parts of said arc, and a valve also disposed in said passage between one part of said arc and said unit.
6. An arc-quenching chamber for an electric circuit interrupter including means forming an arc upon opening of the circuit, comprising a material adapted to yield an arc-extinguishing gas when subjected to the arc heat, casing means defining a passage for directing heated arc gases into the arc path, said material being incorporated in a cartridge-like unit substantially blocking said passage except for gas flow adapted to be inserted in said passage through a wall of said casing means.
7. An arc-quenching chamber for an electric circuit interrupter including means forming an arc upon opening of the circuit, comprising casing means defining a passage for directing heated arc gases from the arc path, and a material adapted to yield an arc-extinguishing gas when subjected to said heated arc gases, said material constituting a unit of substantially honeycomb configuration for defining a plurality of separate paths for said gases so that a comparatively large surface area is presented for contact with said heated arc gases, and means for detachably securing said unit in said passage.
8. An arc-extinguishing chamber for an electric circuit interrupter including fixed and movable contacts, comprising casing structure having an exhaust passage through which the movable contact is operated, said casing means likewise defining a passage leading away from said fixed contact at the initial part of the arc to said exhaust passage by a recurrent shunt path for directing a gas blast into another part of the arc path, and a gas-yielding material constituted as a renewable unit positioned in said passage between said fixed contact and exhaust passage, said material having a comparatively large surface area for contact with the heated arc gases traversing said passage whereby additional arc-extinguishing gas is generated for arc interruption.

HUBERT KORNDÖRFER.

CERTIFICATE OF CORRECTION.

Patent No. 2,155,276.

April 18, 1939.

HUBERT KORNDÖRFER.

It is hereby certified that error appears in the printed specification of the above numbered patent requiring correction as follows: Page 2, first column, line 6, for "ne" read be; and second column, line 12, beginning with "In Fig. 1" strike out all to and including the word and period "operation." in line 32, and insert instead the following sentence -

With this arrangement, the total gas-producing surface is available at low pressures, and hence low currents, for yielding the required gas volume, whereas but a limited surface is required for heavy arc currents where the pressure is already high.;

line 67, for "materially" read material; and that the said Letters Patent should be read with this correction therein that the same may conform to the record of the case in the Patent Office.

Signed and sealed this 6th day of June, A. D. 1939.

Henry Van Arsdale
